ARMORED MOP

Filed March 24, 1930

Harry Herzberg INVENTOR

BY

Martin J. Robinson ATTORNEY

UNITED STATES PATENT OFFICE

HARRY HERTZBERG, OF BROOKLYN, NEW YORK, ASSIGNOR TO HERTZBERG PATENTS INC., OF NEW YORK, N. Y., A CORPORATION OF NEW YORK

ARMORED MOP

Application filed March 24, 1930. Serial No. 438,472.

This invention relates to improvements in mops and particularly of that type which is known as yacht mops or wet mops.

The primary object of the invention is to furnish an improved method for making a mop of this type which is of simple and inexpensive construction and which may be readily and expeditiously manufactured.

It is another object of the invention to provide means in a mop of this type for securing the mop material to the mop handle against rotation thereon and with great rigidity to the cylindrical surface of said handle.

With the foregoing and other objects in view which will appear more clearly as the description progresses, the invention resides in the combination and arrangement of parts and details of construction hereinafter described and claimed.

In the accompanying drawings which form a material part of this disclosure:

Fig. 1 shows a plan of a partly assembled mop before the mop material is fastened to the mop handle.

Fig. 2 is an elevation on line 2—2 of Fig. 1 showing the mop material partly rolled around the mop handle.

Fig. 3 shows an elevation of a nearly finished mop, partly in section on line 3—3 of Fig. 4.

Fig. 4 is a top plan of Fig. 3.

Fig. 5 shows a completely assembled mop partly in section on line 5—5 of Fig. 6.

Fig. 6 is a top plan of the completely finished mop shown in Fig. 5, the cap is broken away as shown in that figure.

Fig. 7 is an elevation of the metallic cap before its assembly on the mop.

Fig. 8 is a top plan of Fig. 7.

Fig. 9 is a detail plan of the blank from which the holding collar 14 is formed.

Fig. 10 is a perspective view of the completed holding collar 14.

Fig. 1 of the drawings shows a mop handle 13 to which is fastened at its lower end a collar 14 which is preferably stamped from non-corrosive sheet metal in the shape shown in Fig. 9 which shows a web 14a provided with teeth 14b along both longitudinal edges

and a plurality of small apertures 14c in the web. The teeth 14b are then bent into a perpendicular position to the web along the lines 14d and the web 14a is rolled to form a cylinder so that a collar, shaped like a spool, is formed on which the teeth form star-shaped flanges as shown in Fig. 10. The collar 14 which is constructed in the above described manner is slipped upon the lower end of mop handle 13 and fastened thereto with suitable tacks 17 which pass through apertures 14c of the web 14a.

A layer of mop material 11, consisting of rope-like strands is placed to lie flat upon two parallel spaced cords 12 and 12a of which the cord 12a is arranged midway between the ends of the mop strands 11. The mop handle 13, provided at one end with the holding collar 14, is so placed upon the mop material that the collar 14 lies in the space between the cords 12 and 12a which are just outside of the collar flanges 14b and the handle 13 extends midway between the longitudinal sides of the mop material parallel thereto. The mop material is then rolled around the mop handle 13 and collar 14 as indicated in Fig. 2 in which it is shown when the rolling operation is only partly completed. The cord 12a is then tied against the mop material so that it clamps the same against the mop handle 13 above collar 14 and cord 12 is tied below the same tying the mop material together and pressing it into the spaces between teeth 14b so that a spherical knob is formed with the collar 14 as a holding core. That part of the mop material 11 which surrounds the handle is then folded downward over the cord 12a upon the lower half of the cords whereby the mop assumes the form illustrated in Fig. 3.

Figs. 7 and 8 illustrate a metallic cap 15 of non-corrosive material which is cylindrical in its lower part and substantially spherical in its upper part, it is provided with a central aperture 15a in the spherical portion and thereby adapted to slip over the mop handle 13. The mantle surface of this cap is provided with a plurality of small apertures 15b.

Cap 15 is slipped over the mop handle 100

- and seated upon the spherical part of the mop material to press tightly against the same, consolidating the outer layer of said material with the inner one and pressing both into the spaces between teeth 14b. A plurality of nails 15 are then driven through the apertures 15b, through the mop material and the web 14a of collar 14 into the handle which completes the mop as shown in Fig. 5.
- 10 The above described construction has many advantages over similar ones now in use. The cap 15 provides an armor-like protection for those parts which join the mop cords, and the nails 16 are rigidly connected to each other at their heads by cap 15 and also at their points by the collar 14 and handle 13. These nails also prevent the removal of the cap from the mop head. The manner of tying the mop cords above and below collar 14 holds the mop material in fixed position, both longitudinally and rotatably, on the handle without looped or twisted wires which generally cut the mop cords when in use for some time.
- 15 20 25 While I have thus described a preferred form of my invention it shall be understood that modifications may be made in the design and arrangement of parts, or in the construction of details which come within the scope and spirit of the invention as claimed.

Having thus described my invention what I claim as new and desire to secure by Letters Patent is:

1. In a mop, a handle, a collar at one end of said handle, a mop head having a knob of mop material tied to said handle and covering said collar, a tuft of said mop material depending from said knob, an outer layer of mop material enclosing said knob and said tuft and a metallic cap which encloses said knob and presses said mop material against said collar.
2. In a mop, a handle, a mop head having a knob of mop material fixed to one end of said handle, a tuft of said material depending from said knob, an outer layer of mop material surrounding said knob and said tuft, a metallic shell surrounding the upper end of said mop head, pressing said outer layer against said knob, and a plurality of teeth rigidly attached to and surrounding said handle and engaging said mop material to prevent its rotation on said handle.
3. In a mop, a handle having a collar thereon at one of its ends, mop material surrounding said collar, tying means fastening said material to said handle above said collar, said material being folded upon itself covering said tying means, a mop head being formed thereby extending below the end of said handle and a metallic cap enclosing the folded part of said mop material.
4. In a mop, a handle having a collar fixed to one of its ends, said collar consisting of a tubular web, and an annular flange surround-

ing said web forming teeth on said web, mop material tied to said handle above said collar and tied together below the end of said handle to form a knob and a tuft depending therefrom, an outer layer of mop material enclosing said knob and means to press the layers of mop material against said teeth.

5. In a mop, a handle, a mop head having a knob of mop material tied to one end of said handle, a tuft of said material depending from said knob, an outer layer of mop material enclosing said knob and said tuft and a metallic collar within said knob fixed to said handle, a toothed flange on said collar engaging said mop material, tying means above said collar pressing said mop material against said handle, tying means below said collar pressing said material against said teeth.

6. In a mop, a handle, a mop head having a knob of mop material fixed to said handle, mop material forming a tuft on said knob extending below said handle, a collar having a toothed flange attached to said handle within said knob and a metallic cap enclosing said knob.

Signed at Brooklyn, in the county of Kings and State of New York this 12th day of March, A. D. 1930.

HARRY HERTZBERG.
